UNITED STATES PATENT OFFICE.

ALBERT H. MANWARING, OF PHILADELPHIA, PENNSYLVANIA.

SECTIONAL SUPPORT FOR PENDENT LIGHT-FIXTURES.

1,199,587.

Specification of Letters Patent. Patented Sept. 26, 1916.

Application filed November 1, 1913. Serial No. 798,703.

To all whom it may concern:

Be it known that I, ALBERT H. MANWARING, a citizen of the United States, residing in Philadelphia, Pennsylvania, have 5 invented certain Improvements in Sectional Supports for Pendent Light-Fixtures, of which the following is a specification.

My invention relates to means for supporting lighting fixtures, and the object of 10 my invention is to provide a tubular sectional structure, more particularly employed for the support of electric lighting fixtures and constructed for the purpose of carrying and concealing the current conducting wires. In the present instance, the 15 supporting structure is in the form of a tube, which may be rectangular or of other suitable shape in cross section.

A further feature of my invention is to 20 employ such supporting means with a sectional supporting rim for the shade or globe employed with the lighting fixture; which rim may be hung from one or a plurality of the tubular, sectional, wire-carrying supporting members.

These and other features of my invention are more fully described hereinafter, reference being had to the accompanying drawings, in which:

30 Figure 1, is a view in elevation of a lighting fixture, showing one form of sectional supporting means and sectional shade holder within the scope of my present invention; Fig. 2, is an enlarged view of a 35 portion of the sectional support and sectional shade holder shown in Fig. 1; Fig. 3, is a plan view of the same; Fig. 4, is an enlarged face view of a portion of the structure shown in Fig. 2; Fig. 5, is a vertical 40 sectional view taken on the line 5—5, Fig. 4; Fig. 6, is a sectional view on the line 6—6, Fig. 4; Fig. 7, is a sectional view on the line 7—7, Fig. 4; Fig. 8, is a perspective view of the end of one of the sections 45 shown in Figs. 2 and 4; Fig. 9, is an enlarged sectional view on the line 9—9, Fig. 2; Fig. 10, is a sectional view on the line 10—10, Fig. 2; Fig. 11, is a sectional view on the line 11—11, Fig. 2, and Figs. 12 50 and 13, are views illustrating other forms of tubular or hollow sections within the scope of my invention.

The important feature of my present invention is the idea of having a sectional tubular support for lighting fixtures which can be built up as desired by adding more

sections. The sections are hollow, usually tubular, and carry the electric wires or cords inside the same.

In the structure shown in Figs. 1 and 2, 60 the support is made up of a plurality of plain sections 1, which may be in pairs, and special sections 2 having U-shaped portions 2^a for attachment with the sections 1, and single portions 2^b for attachment to a ceiling support 3 and a globe or shade support 5. The several sections may be rectangular or of other shape in cross section and they are hollow to receive the wires 7. Intermediate the special sections 2 and the 70 ceiling support and the special sections 2 and the globe support, I provide, in the present arrangement, connecting sections 6. All of these sections are hollow, and they may be connected together to form the desired support in the following manner: 75 Each tubular section may have a cup-shaped end 1^a, in the present instance disposed at the bottom of the section as employed in the support. These cup-shaped 80 ends are relatively deep, and across the widest portion of the same, on two sides, I make a cut or saw-kerf 8 extending entirely through the wall of metal. At the opposite ends of these sections, the wall at the 85 widest point is cut away on both sides as indicated at 9; the width of such cuts being a little greater than the width of the walls 10 of the cup-shaped portion between the kerf or cut 8 and the end of the section. 90 The narrow ends of the sections are then telescoped within the cup-shaped ends, and the walls 10 of the latter are pressed into the spaces formed by the cuts 9 of the end of the next link and such walls, when depressed, will engage the end walls formed by the cut-out portions 9 and lock such 95 tubular sections together.

The sectional supporting means are suspended from a suitable ceiling support 3, 100 which may be fastened adjacent the ceiling in any well known manner. Carried by this member are hollow yoke-shaped members 11, the separate ends of which may be threaded and pass through openings 12 in the ceiling 105 support 3, and be secured thereto in any suitable manner. The lower ends of the members 11 are attached to the sections 1 by connecting members 6. The conducting wires 7 pass through the several hollow tubular 110 members making up the sectional support, and they are connected in the usual manner.

to the source of current supply and the lamp sockets, respectively.

The lower ends of the sectional supports are connected to portions of a sectional shade holder made up of links 15, suitably connected together; in the present instance such links or sections having straps 16 at one end adapted to enter slots 17 at the other end of an adjacent link and be folded back 10 to effect a lock. These shade supporting sections are formed originally on such a curve or radius as to permit of being built up of a greater or less number of pieces, as may be desired, to fit the rims 18 of different 15 sized globes 19. Certain of the links carry plates 20 to which the supports are attached; being secured to said links by screws 21, and these plates carry threaded members 22 to which electric lamp socket holders may be 20 attached, and the wires 7 which are brought down through the hollow sections are passed through said threaded members 22, which are hollow. It will be understood, of course, that other forms of sectional shade 25 holders may be employed.

As the shade supporting rim is flexible and made up of independent, interchangeable units, it will be readily understood that the size of the shade support may be varied 30 by adding to or removing links or sections. When large shades are to be supported, a plurality of supports are generally employed, three or four, as may be desired. Smaller shades may only require two, and 35 in some instances a single support may be employed; the shade or globe support being provided with a frame or spider to which such support may be attached.

The important feature of this invention 40 is the adjustability of the sectional support. The support proper, consisting of hollow separable sections which are preferably rigidly connected together, may be readily connected and disconnected; permitting an instant lengthening or shortening of the same to suit conditions which can not be foreseen when the placement of the structure is first proposed. If desired, portions 45 of the tubular sections may consist of more than one unit. At the same time, the wires are concealed so that all that is in view are the tubular bar supports.

Any form of shade holder or shade holding means may be employed with my improved supports; the latter may have hooks 55 to engage the flange of a globe, inside or out, or the latter may have an adjustable spider frame to which the supports may be attached; the supporting rim in such instance being omitted.

If desired, two or more of the sectional unit links may be joined in one piece for convenience.

The several parts of the structure may be cast, made of pressed-up sheet metal, or 65 otherwise constructed, as may be convenient or desirable.

I claim:

1. The combination, in supporting means for lighting fixtures, of a plurality of hollow 70 sections each of the same shape and arranged to carry conducting wires, each of said sections having their respective ends transversely slit and shaped for direct telescopic connection with adjacent sections, the 75 end of one section entering the end of a succeeding section, and coöperative securing means in the telescoping ends formed by the transversely slit portions for locking the sections together.

2. The combination, in supporting means for lighting fixtures, of a plurality of independent hollow sections receiving conducting wires, and connections for said sections comprising compressible walls carried by 85 each section for engagement with the telescopic portion of an adjacent section.

3. The combination, in supporting means for lighting fixtures, of a support made up of a plurality of hollow tubular sections to 90 receive and conceal conducting wires, each of said sections being made up of a sheet metal body, one end having opposite walls cut away, and the opposite end having compressible walls for engagement with the 95 spaces formed by the cut away portions of an adjacent hollow tubular section.

In testimony whereof, I have signed my name to this specification, in the presence of two subscribing witnesses.

ALBERT H. MANWARING.
